CLAIM

The ornamental design for seating device with signage for athletic events, as shown and described.

DESCRIPTION

FIG. 1 is a front view of a seating device showing our new design.

FIG. 2 is a rear view thereof.

FIG. 3 is a side view thereof; and,

FIG. 4 is a perspective view thereof.

The broken lines showing letters on the backrest panel in FIGS. 1, 2 and 4 are for illustrative purposes only and form no part of the claimed design.
